GLOW DISCHARGE SWITCH

Adolph Warsher, Maywood, N. J., assignor to
Maxwell M. Bilofsky, Newark, N. J.

Application June 6, 1944, Serial No. 538,987

7 Claims. (Cl. 200—113.5)

1

It is among the objects of the invention to provide a glow discharge switch, of simple and relatively inexpensive construction, which shall be applicable in all relations where it is desired automatically and sensitively to control a circuit in differentiated manner, depending upon the magnitude of heating evolved by the glow discharge gap, and in which the operation and control is effected with complete safety even though the switch be used in environment where explosive gas mixtures may be encountered.

The invention has an important application to thermionic lamp starters of the glow discharge type and in that application further and more specialized objects are to provide a device of the above type which shall readily be replaceable for the conventional glow discharge starter, and which shall in addition to its primary lamp starting function perform the additional function of promptly and automatically inhibiting the intermittent flashing of a lamp that has become defective, as for instance, by loss of emissive coating from its electrodes and which shall do so without the drastic curtailment in life incurred with the use of conventional glow discharge switches under such intermittent flashing and yet, under normal operating conditions, with a perfect lamp, the starter shall not add in the least to the wattage consumed in lamp operation.

Generally stated, the invention involves enclosing in the hermetically sealed envelope for the bimetal strip used in the conventional bimetal glow switch starter for thermionic devices, a second and less sensitive thermally responsive member that, upon sufficient deflection thereof, effects a circuit alternative to and distinct from that of the normal discharge gap and in which circuit sufficient heat is evolved to maintain the additional heat responsive element deflected until the circuit to the switch is opened.

In the accompanying drawings in which are shown one or more of various possible embodiments of the several features of the invention,

Fig. 1 is a sectional view partly in perspective, showing one embodiment of the glow discharge switch,

Fig. 2 is a perspective schematic detail thereof on a larger scale,

Figs. 3 and 4 are views similar to Fig. 1 of modifications,

Fig. 5 is a plan view of the embodiment of Fig. 4,

Fig. 6 is a view similar to Fig. 3 of a further modification, and

Fig. 7 is a circuit diagram showing the ap-

2

plication of the glow discharge switch as the starter for a thermionic lamp.

Referring to Fig. 1, the switch comprises a hermetically sealed envelope 10, desirably of glass, exhausted of air through tube 11 and charged with noble gas such as neon under very low pressure. Through the stem 14 of the envelope extend the two terminals 12 and 13. Upon post 15 of the terminal 12 is affixed the main heat responsive member, desirably bi-metal strip 16, which carries a contact 17, adapted to coact with contact 17' upon the end of the companion electrode 19 carried upon post 18. Electrode 19 is a switching strip, desirably also of bi-metal but less sensitive and more sluggish in its response to heat than is the main strip 16, so that in normal operation, it remains substantially undeflected, even though strip 16 has deflected substantially. Under excessive heat, however, the switch strip 19 is deflected in the same direction as the main strip 16. Movable with the switching strip is a contact 20 normally open, but adapted upon sufficient deflection of the switching strip to establish circuit to an auxiliary electrode 21 which faces the switching strip 19. The contact 20 when moved by the deflected switching strip 19 closes circuit through a connecting wire 22 from the post 15 that carries the main strip 16 to the auxiliary electrode 21, which is spaced from switching strip 19 and normally out of circuit. The glow discharge gap G' between the switching strip 19 and the auxiliary anode 21 is designed to have a considerably lower voltage drop than the main discharge gap G. This is accomplished by providing surfaces with lower work functions, as for instance, by coating auxiliary anode 21 with electron emissive material 23 and preferably coating the corresponding face of switching strip 19 with like material, illustratively with barium or strontium oxides or the like, or combinations thereof.

While any of numerous mechanical arrangements may be provided for correlating the auxiliary anode 21 and the contact 20 with each other and with the switching strip, a desirably specific construction is that shown in Figs. 1 and 2. To that end a short rigid support wire 24 is carried by the upper end of the switching strip 19 and mounts a glass bead 25 embedding the free end thereof. The bead has also embedded therein but spaced from wire 24 a carrying wire 26 to which is welded a switching member, desirably in the form of a cross wire 22. In Fig. 1 the switching wire 22 carries the contact 20 at its inturned left end 27. The right

end 28 of said wire 22 is downturned and has affixed rigidly thereto the auxiliary anode 21 above referred to.

Under normal operation, the heat evolved in glow discharge gap G causes deflection of main bi-metal strip 16, to cause contacts 17 and 17' to touch, thereby to quench the discharge gap so that the glow discharge switch cools and its contacts 17-17' reopen. However, under any eventual evolution of excessive heat in gap G, the less sensitive switching strip 19 will deflect toward the right, and carry with it the switching wire 22 to bring the contact 20 thereon into engagement with terminal post 15, and thereby impose upon the auxiliary anode 21 the potential of terminal 15, the switching strip 19 being maintained under the potential of terminal 13. The switching strip in its deflection does not approach the auxiliary anode 21, since the latter is carried thereby and moves therewith, so that the distance therebetween remains constant. Since gap G' has a lower work potential than gap G and the two gaps cannot be maintained in parallel, the glow discharge now is established and maintained across gap G', and gap G is extinguished. The heat evolved in gap G' is sufficient, however, to maintain the bi-metal switching strip 19 in the deflected position, so that the switch remains in the setting last described until the circuit to the glow discharge switch is interrupted.

Since the bi-metal strips 16 and 19 flex in the same direction, the glow discharge switch is inherently self-compensating and even a considerable increase in the ambient temperature would not cause the contacts 17 and 17' to touch. It will be understood that wire 22 could be directed to cause contact 20 to engage the bi-metal strip 16 or a contact thereon, instead of engaging the rod 15 as shown.

In the embodiment of Figs. 3, 4 and 5 are shown arrangements utilizing an electric heater in the form of an ohmic resistance, rather than an auxiliary discharge gap, to maintain the switching strip in deflected position after functioning thereof.

In the embodiment of Fig. 3, the post 30 and main bi-metal strip 31 are of conventional construction, as is the coacting contact 32 which, however, is mounted upon a more sluggish bi-metal switching strip 33 in turn supported by the second terminal post 34. The contact 32 of said switching strip has in the path of deflection thereof a contact 36 on the end of an electric heater 37 connected by wire 38 to the terminal post 30. Desirably, contact 36 is affixed in insulating relation to wire 38 which is relatively stiff. This may be accomplished by embedding the contact end in a glass bead 39 encompassing and anchored to wire 38. Obviously, under prolonged heat, switching strip 33 is deflected toward the right to close circuit to the ohmic resistance 37 which operates as a heater to maintain the switching strip 33 deflected and to bridge the normal starting gap and does so until the circuit to the switch is opened.

In the embodiment of Figs. 4 and 5, the less heat sensitive bi-metal switching strip 40 which flexes toward the left is mounted on terminal rod 41 and the main bi-metal strip 42 is mounted upon the upper end of said switching strip by an intervening connector rod 43. The main strip 42 flexes toward the right and coacts with a fixed anode 44 on the end of a second terminal rod 45. The latter rod is joined by connector wire 46 to an electric heater 47 near the switching

strip 40. The lower end of the resistance 47 is connected to a terminal post 48 insulated as, for instance, by a glass bead 49 from a wire 50, to the upper end of which is connected the upper end of resistance 47, the lower end of wire 50 being embedded in said bead at a distance from the bead embedded upper end of wire 48.

As will be apparent, under excessive heat evolution, the deflection of the switching strip 40 toward the left displaces the main strip 42 away from the fixed anode 44, until strip 40 engages the arm 50' of wire 50. Circuit is now established from terminal 41 through switching strip 40, wire 50 and resistance 47 to the opposite terminal 48. The heat evolved by the resistor 47 maintains the switching strip 40 deflected and bridges the gap between strip 42 and anode 44 until the main switch is opened.

In the embodiment of Fig. 6, the terminal post 60 carries the main bi-metal strip 61 of U-form, facing in one direction and the bi-metal switching strip 62 also of U-form but of more sluggish action facing in the opposite direction. The contact 63 of the main bi-metal strip 61 coacts with the anode 64 on the second terminal post 65. The electric heater resistance 67 is near but spaced from switching strip 62 and in the path of movement of the free end thereof.

The lower end of heater 67 is affixed to post 55, the upper end of which is embedded in glass bead 56 in which is embedded the lower end of wire 57 that mounts the upper end of heater 67. Conductor 66 externally of the envelope connects post 65 to post 55. Thus, in operation, when the switching strip is deflected under prolonged heat, it closes circuit to the resistance 67 by engagement of contact 68 on the switching strip with contact 69 upon the upper heater mounting wire 57. The heat evolved in heater 67 is sufficient to keep the switching strip 62 deflected until the main circuit is opened. With the resistance thus in circuit the glow discharge gap between strip 61 and anode 64 is bridged by heater 67.

The entire glow discharge switch in each of its embodiments is hermetically sealed in its envelope 10 so that it may be used safely, even in an atmosphere in which explosive mixtures are sometimes present.

In Fig. 7 is shown the circuit diagram of an important application of the glow discharge switch in one of its various uses, i. e., for the starting of a conventional thermionic lamp L with electrode filaments at the opposite ends thereof, each coated with an emissive coating of barium oxide or strontium oxide according to conventional practice.

The glow switch starter S of any of the embodiments shown is in the starting circuit 70, which connects lamp electrodes 71 and 72 in series, for electrically heating the same. An iron core ballast coil 73 is in the line and the lowering of the power factor of the system due to its operation is compensated for by condenser 74 across the line, all in accordance with conventional practice.

In the operation of the conventional glow switch starter, the applied voltage is at the outset sufficient to cause the glow discharge in gap G, but is insufficient to cause arcing of the lamp 70 L. If starter S is of the construction shown in Figs. 1 and 2, the bimetal strip 16 thereof under the heat of the glow discharge, deflects to close circuit to contact 17' while storing energy in ballast coil 73. The glow discharge is thus interrupted with resultant cooling and contraction of

the bimetal strip 16 away from contact 17. As a result of this opening of the starter circuit, the impulse from the ballast coil 13 tends to start the arc in the lamp L across its now heated electrodes 11 and 12 and the starting cycle set forth is resumed until the arc in the lamp L has actually been struck and since such arc when once maintained requires voltage less than that required to initiate the glow discharge in the starter switch S the latter remains out of action.

Should the lamp become defective, as for instance, due to the loss of emissive material from one or both of its electrodes, so that the lamp will falter instead of maintaining its arc, the conventional glow switch starter (devoid of the present improvement), would repeat the cycle above set forth and cause the lamp intermittently to flash on and off, to the annoyance of the user and with very short life of the glow discharge switch.

With the glow switch of the present invention, however (illustratively of the embodiment of Figs. 1 and 2), should the glow discharge in gap G be maintained for an abnormal length of time, due to the slowness in starting or restarting of a defective lamp, the less sensitive bi-metal strip 19, which in normal operation will not move, is caused to flex, to bring the switching wire 22 into engagement with the post 15 and to apply the potential of said post upon the auxiliary anode 21. By reason of the lower work function of the electrodes of glow discharge gap G', the glow discharge is promptly set up between switching plate 19 and auxiliary anode 21. The glow discharge in gap G' evolves sufficient heat to maintain the bi-metal strip 19 deflected and that glow discharge is thus maintained as long as the main switch 75 controlling the lamp L is closed.

By reason of its electrodes of lower work function, the existence of the glow discharge across gap G' precludes the possibility of the glow discharge resuming across the main discharge gap G. The intermittent flashing of a defective lamp L is therefore precluded as is the repetition of the cycle of operations of the bi-metal strip 16. Accordingly, the glow discharge switch of the present invention is not subject to rapid wear and will serve for many thousands of hours use.

From the foregoing description, the mode of operation of the glow discharge switches of the embodiments of Figs. 3 to 6, when used as thermionic lamp starters, will be clear without the need for further description.

In each embodiment, it is seen that the use of the present improvement, does not involve the slightest alteration in the mode of operation as compared with the operation of a conventional glow starter switch upon a perfect lamp. The presence of the added safety switching feature does not add in the least to the power consumption as long as the glow starter switch of the present invention is used with a good lamp.

The glow discharge switch in each of its embodiments is, of course, useful as an automatic control switch in a wide variety of applications, in fact, in any relation in which the evolution of heat in the switch, upon exceeding a predetermined minimum is automatically to effect some switching in the circuit connections.

The glow switch starter is a unit of small bulk, in fact in its lamp starter form, it is of bulk so small that there is no need for alteration in the thermionic lamp fixtures now in use that are designed for conventional glow switch starters, to enable replacement of the latter by the im-

proved glow switch starter of the present invention.

By the term "glow discharge switch" as used in the claims is meant a unit of the general character described, which is charged with a noble gas or mixture of noble gases at pressure such as to develop a glow discharge across its electrodes at voltage controlling a step in the operation of the system or device with which it is used.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A glow discharge switch comprising an envelope having a pair of bi-metal electrodes spaced for glow discharge therebetween, one of said electrodes being less sensitive to heat than the other and flexing away from the latter to serve as a switching electrode under the prolonged evolution of heat in the glow discharge gap; an auxiliary electrode spaced from said switching electrode and out of circuit under normal operation, and means under control of said switching electrode and carried thereby to close the circuit to said auxiliary electrode thereby to effect a glow discharge between the switching and the auxiliary electrode, said latter glow discharge circuit having sufficient heat evolution to maintain the switching electrode in its deflected position as long as the circuit remains closed.

2. A glow discharge switch, comprising an envelope having therein a pair of bi-metal strips spaced for a main glow discharge therebetween, terminals carrying the same, one of said strips being of less heat sensitivity than the other, being arranged to deflect away under prolonged heating and constituting a switching strip, an auxiliary electrode movable with and spaced from said switching strip for alternative glow discharge therebetween and having electrodes of lower work function than those of said main glow discharge, and means responding to the movement of said latter strip for electrically connecting the auxiliary electrode with the terminal of the other electrode to initiate the alternative glow discharge, the switching strip being exposed to the heat generated by said alternative glow discharge and maintaining the latter until the circuit to the glow discharge switch is opened.

3. A glow discharge switch comprising an envelope having fixed terminals extending thereto, bi-metal strips affixed to said terminals determining a discharge gap therebetween, and having coating contact portions normally spaced from each other, one of said bi-metal strips being less sensitive to heat than the other and serving as a switching strip upon deflection thereof under prolonged heating, an auxiliary electrode movable with and insulated from said switching strip, said auxiliary electrode and said switching strip being spaced from each other and defining an alternative glow discharge gap therebetween, a connector under control of said switching strip for establishing electrical contact from said auxiliary electrode to the terminal of the other strip, said switching strip being exposed to the heat evolved in the alternative glow discharge gap,

thereby to maintain said switching strip deflected.

4. A glow discharge switch comprising a hermetically sealed envelope, a pair of electrode posts extending thereinto, a main bi-metal strip rigid at its root with one of said posts, a switching bi-metal strip rigid at its root with the other of said posts, said strips being spaced for a main glow discharge gap therebetween, a switching member carried by said switching strip and insulated with respect thereto, an auxiliary electrode carried by said switching member near one end thereof facing but spaced from said switching strip for alternative glow discharge gap having elements of work function lower than those of said main glow discharge gap, said switching member being normally spaced at its opposite end from the electrode post of the main bi-metal strip and closing circuit thereto by the movement of the switching strip under prolonged heat, the heat evolved in the alternative glow discharge gap being sufficient to maintain the switching strip deflected until circuit is opened.

5. A glow discharge switch comprising a hermetically sealed envelope having a pair of bi-metal electrodes therein spaced for glow discharge therebetween of higher work function, terminals therefor, said electrodes including a main bi-metal strip, a bi-metal switching strip less sensitive to heat than said main strip so as to deflect materially only under prolonged heat, a switching member carried by said switching strip and insulated therefrom, an auxiliary electrode carried by one end of said switching member, said auxiliary electrode and said switching strip being spaced to define an alternative glow discharge gap therebetween, the other end of said switching member being adjacent the main bi-metal strip and serving to switch said auxiliary electrode into circuit by deflection of the switching strip away from the main strip under applied

heat, the heat evolved in the alternative glow discharge gap being sufficient to keep the switching strip deflected until the circuit is interrupted.

6. The combination recited in claim 5 in which a glass bead wire mounted upon the switching strip mounts the switching member in electrically insulating relation with respect thereto.

7. A glow discharge switch comprising a hermetically sealed envelope having terminal posts therein, a bi-metal main strip on one of said posts, a coacting bi-metal switching strip on the other of said posts, and of lesser rate of deflection than said main strip and a switching wire carried by said switching strip and insulated therefrom, said wire having a downturned end portion, an auxiliary electrode affixed thereto, facing said switching strip and having an emissive coating thereon, the other end of said wire being movable under the deflection of said switching strip to apply potential from the post carrying the main strip to the auxiliary electrode, the discharge gap to said auxiliary electrode having elements of lower work function than that across the bi-metal strips, the heat evolved in the discharge gap to said auxiliary electrode being sufficient to maintain the switching strip deflected until the circuit is opened.
